UNITED STATES PATENT OFFICE.

RALPH ABRAHAM SCHOENBERG, OF NEW YORK, N. Y., ASSIGNOR TO IDA S. ROSENHEIM,
OF NEW YORK, N. Y.

MEANS FOR OPERATING SWITCH MECHANISM.

1,176,102.

Specification of Letters Patent. Patented Mar. 21, 1916.

Original application filed February 9, 1914, Serial No. 817,472. Divided and this application filed May 22, 1915. Serial No. 29,929.

To all whom it may concern:

Be it known that I, RALPH A. SCHOENBERG, of New York, in the county of New York and State of New York, have invented new and useful Means for Operating Switch Mechanism, of which the following is a specification, this application being a division of my application filed February 9, 1914, Serial No. 817,472.

My invention relates to means for operating switch mechanisms and particularly when such mechanisms are placed in sockets or other receptacles especially when adapted for carrying electric light lamps or attachment plugs.

In the case of sockets or other receptacles it is highly desirable to do away with the unsightliness caused by protruding actuators, such as keys, chains and push-buttons. These actuators are a distinct drawback as a matter of appearance and particularly in the case of very fine fixtures and require not only perforation of the socket or other receptacle but also perforation of the husk or socket cover when the latter is used as well as alinement of the perforations of socket and husk.

One object of my invention is to do away with such protruding actuators and another object is to provide simple but efficient operating means and other objects will be described below.

My invention consists partly in providing a support for an electrical appliance such, for example, as a lamp or attachment plug movable longitudinally in one direction to make the circuit and movable longitudinally in the other direction to break the circuit.

A feature consists in having the support move outwardly to make the circuit and inwardly to break the circuit.

Another feature consists in providing two relatively movable members one of which has a spring to engage a cam on the other to provide such relative movement.

Other features will be described below.

In the drawings: Figure 1 is a central longitudinal sectional view of a device embodying my invention: Fig. 2 is a view like Fig. 1 but showing the parts in different positions; Fig. 3 is an elevation of the two porcelain blocks of the device shown in Fig. 2 showing the parts mounted on said blocks; Fig. 4 is an elevation of the stationary por-

celain block hereinafter described; Fig. 5 is a plan view of the porcelain block shown in Fig. 4; Fig. 6 is a section on line 6—6 of Fig. 2; Fig. 7 is a section on line 7—7 of Fig. 2; Fig. 8 is an elevation of the inner face of one of the two counterpart porcelain block sections which form the porcelain block shown in Fig. 4; Fig. 9 is a central longitudinal section of another form of my invention; Fig. 10 is a plan view of an attachment particularly designed for use with the forms of my invention shown in Figs. 1 and 9; Fig. 11 shows the attachment of Fig. 10 applied to the lamp of one of my devices which may be constructed like that shown in Figs. 1 or 9; and Fig. 12 illustrates another modification.

In Figs. 1 to 8 inclusive the stationary porcelain block is made up of two counterpart pieces of porcelain 1, Fig. 8, and is provided with a contact finger 2 which co-operates with a spring contact finger 3. The two pieces of porcelain 1 which make up the stationary porcelain block are provided upon their inner faces with registering recesses 4 within which the springs 5 are pocketed. The movable porcelain block 6 has the screw shell 7 fastened to it by means of bolts 8 and the center contact 9 is screwed onto the lower end of a post 10 so as to fasten said post to said block. The two pieces of porcelain 1 are made upon their inner faces with registering recesses 11 which pocket and support a metal contact ring 12 that is provided with two downwardly extending flexible contact fingers 13 co-operating with an enlargement 14 provided on the post 10. The contact ring 12 is made with an extension 15 that is fastened to the porcelain block 1 by means of a bolt 16 which serves also to hold the two parts of the porcelain block together and has a binding post for a line wire 17. The other line wire 18 is connected with another binding post bolt 19 which fastens the contact member 2 to the stationary porcelain block and serves also to hold the two sections of said block together. In this form of my invention the contacts 2 and 3 are permanently in engagement and the circuit is opened and closed merely by moving the enlargement 14 into and out of engagement with the contact fingers 13, through in and out movement of the screw shell 7 and post

10. In this form of my invention the cam or enlargement 20 on post 10 has two cam faces each of which acts with one of the springs 5 to yieldingly hold the blocks 1 and 6 against relative movement but when movement of block 6 is manually started acts to provide a quick make and quick break between the enlargement 14 and contact fingers 13 by an endwise or longitudinal movement of the post 10 and screw shell 7, such movement outwardly making the circuit and inwardly breaking it.

In the form of my invention shown in Fig. 9 the screw shell 7 is secured to the underside of a porcelain block 21 provided with a center contact 9 screwed onto the lower threaded extremity of a post 22 which is thus rigidly connected with said porcelain block by the center contact. The post 22 extends upwardly through the porcelain block 1 which for construction reasons may be made in two pieces fastened together by screws 23. Near its upper end post 22 is made with a beveled cam or enlargement 20 having two cam faces coöperating with a pair of springs 5 pocketed within recesses 4 within the block 1 (see Fig. 8). The post 22 carries a spring contact 24 which coöperates with a contact 25 fastened by means of a bolt 26 to the porcelain block 1, said bolt serving also as the binding post for one of the line wires 27. The other line wire 28 is connected with a binding post 29 forming part of a fixed contact member 30 mounted within block 1. The lower end of the fixed contact member 30 extends below porcelain block 1 and into a notch formed in the porcelain block 21 where it is provided with an enlargement or head 31. The head 31 operates with a pair of spring jaws or contacts 32 riveted or otherwise secured to and in electrical contact with the screw threaded shell 7. Normally the porcelain block 21 will occupy the position shown in Fig. 9 with the contacts 24 and 25 separated and the contacts 30 and 32 separated, said block being held in this position by the engagement of the springs 5 with the underside of the beveled cam or enlargement 20. When it is desired to close the circuit through this switch device the lamp, attachment plug or other device connected with the screw shell 3 is pulled downwardly until the largest part of the beveled enlargement 20 passes the angular portions of the springs 5 whereupon said springs act upon the upper beveled side of the enlargement 20 to accelerate the downward movement of post 22 and parts connected therewith, thus producing a quick make between contacts 24 and 25 and contacts 31 and 32 and this by a longitudinal movement of the bridging member. When post 22 is thus forced downwardly by the springs 5 the shoulder 33 immediately under the enlargement 20 engages

the bottom 34 of recess 4 which serves as a stop to limit the downward movement of post 22. When it is desired to open the circuit of the lamp, attachment plug or other device connected with the screw shell 3, said device is shoved inwardly carrying with it the screw shell 3, block 21 and post 22. As the largest part of the enlargement passes the angular ends of the springs 5 the latter act upon the lower beveled side of said enlargement to accelerate the upward movement of post 22 and parts connected therewith thereby producing a quick break at the contacts 24 and 25 and contacts 30 and 32. When the post 22 occupies either of its two positions it is yieldingly held thereby by the engagement of the springs 5 with the beveled enlargement 20. As will be observed in this form of my invention the screw shell 3 may be shifted from closed position to open position or vice versa and when so shifted the springs 5 serve to hold it against return movement. In this form of my invention the porcelain block 21 and screw shell 7, like corresponding parts 6 and 7 in Fig. 1, constitute the supporting member for the supported member which may be a lamp, attachment plug or other device. In both forms of my invention so far described as well as in that presently to be described the insulating lining 35 and shell 36 are without perforations for laterally projecting actuators for the reason just given, namely, that I do not use laterally projecting actuators which require perforation of the insulating lining and of the outer shell.

When my improved switch device is used to hold a lamp and is arranged in a more or less elevated position as shown in Fig. 11 I prefer to provide the lamp with the attachment shown in Figs. 10 and 11. This attachment comprises two metal strips one of which 37 is bent near its middle to form a loop 38 adapted to extend half way around the shank of the bulb 39 with the ends 40 of said part bent outwardly and having their extremities hooked as at 41. The other part of this attachment comprises a metal strip 42 bent to form a loop to extend around the other half of the bulb and having its extremities fastened to the part 38 by means of two screws 43. This form of attachment may be used with any one of the switch devices herein shown and by grasping either or both of the arms 40 the operator may conveniently move the lamp to operate the switch device.

In Fig. 12 my invention comprises a screw shell 7 secured to a movable porcelain block 6 carrying a spring contact finger 44 coöperating with a contact 45. The block 6 carries a center contact 9 which fastens a stem 10 thereto, said stem, like the stem 10 of Fig. 1, coöperating with a pair of contact fingers 13 projecting from a metal ring 15.

The ring 15 is made with an extension 45 provided near its extremity with a threaded hole into which is screwed the threaded end of the shank of another center contact 46. 5 The stem 10 is, like the stem 10 of Fig. 1, made with a cam or enlargement 20 coöperating with a pair of springs 5 pocketed within a stationary porcelain body 47. At 10 its lower end the body 47 is made with a skirt 48 inclosing screw shell 7, and at its upper end with a plug 49 upon the outside of which is arranged a second screw shell 50. This screw shell 50 is held in place on plug 49 by lugs 51 which are bent inwardly into 15 recesses 52, and carries the contact 45 which may be integral therewith or soldered thereto. The porcelain body 47 may be made in two counterpart sections fastened together by bolts 53. The shell 50 and center contact 46 constitute engaging means 20 provided upon this form to attach to the terminals in the mouth of an ordinary socket.

In Fig. 12 I have shown my invention embodied in a switch connector or union adapted to be used, for instance, to connect an ordinary lamp or cord plug with an ordinary socket.

What I claim is:

- 30 1. A device of the character described comprising switch mechanism including an immovable contact and a contact movable into and out of engagement with said immovable contact; a support movable longitudinally in one direction to make the circuit and in the opposite direction to break the circuit through said switch mechanism; and an electrical appliance carried by the support and having a terminal in circuit with said switch mechanism.
- 40 2. A device of the character described comprising switch mechanism including an immovable contact and a contact movable into and out of engagement with said immovable contact; a support movable outwardly to make the circuit through said switch mechanism; and an electrical appliance carried by the support and having a terminal in circuit with said switch mechanism.
- 50 3. A device of the character described comprising two blocks of insulating material connected together with provision for limited relative movement toward and from each other; a stem mounted on one block and provided with a cam; a spring on the other block coöperating with the cam to hold the blocks yieldingly against relative displacement and to effect a quick relative movement thereof after said relative movement has been manually started; and a pair of circuit-controlling contacts that are closed by relative movement of said blocks in one direction and opened by relative 65 movement in the opposite direction.

4. A device of the character described comprising two blocks of insulating material connected together with provision for limited relative movement toward and from each other; a stem mounted on one block 70 provided with a cam; and a spring on the other block coöperating with the cam to hold the blocks yieldingly against relative displacement and to effect a quick relative movement thereof after said relative movement has been manually started; and a contact on said other block coöperating with said stem to control the circuit of the device.

5. A device of the character described comprising two blocks of insulating material 80 connected together with provision for limited relative movement toward and from each other; a stem mounted on one block provided with a cam; and a spring on the other block coöperating with the cam to 85 hold the blocks yieldingly against relative displacement in either direction and to effect a quick relative movement thereof after said relative movement has been manually started; and a contact on said other block 90 coöperating with said stem to control the circuit of the device.

6. A device of the character described comprising two blocks of insulating material 95 connected together with provision for limited relative movement toward and from each other; a stem mounted on one block provided with a pair of cam surfaces; a pair of springs carried by the other block engaging opposite sides of the stem and coöperating with the cam surfaces to hold the blocks yieldingly against relative displacement and to effect a quick relative movement thereof after said relative movement has been manually started; and a contact on 100 said other block coöperating with said stem to control the circuit of the device.

7. A device of the character described comprising two blocks of insulating material 110 connected together with provision for limited relative movement toward and from each other; a pair of terminals on one of said blocks; a screw shell, center contact and a stem mounted on the other block, said stem being provided with a cam; and a 11 spring on the first-mentioned block coöperating with the cam to hold the blocks yieldingly against displacement and to effect a quick relative movement thereof after said relative movement has been manually started to complete the circuit through said terminals and screw shell and center contact.

8. A device of the character described comprising two blocks of insulating material 120 connected together with provision for limited relative movement toward and from each other; a pair of terminals on one block; a pair of terminals on the other block, each coöperating with one of the terminals on the first-mentioned block; a stem mounted 130

- on one block and provided with a cam; a spring on the other block coöperating with the cam to hold the block yieldingly against relative displacement and to effect a quick relative movement thereof after said relative movement has been manually started to bring one of said pairs of terminals into or out of contact with the other pair of terminals.
- 10 9. A device of the character described comprising a longitudinally movable sup-

port; an electrical appliance carried by the support; and an attachment separate from said support to move said appliance and having a portion removably connected to said appliance and having another portion projecting from the first portion, said other portion being adapted to be grasped by the hand of the user to move said attachment and said appliance longitudinally. 15

RALPH ABRAHAM SCHOENBERG.
